UNITED STATES PATENT OFFICE.

NATHANIEL R. POTTER, OF ROCHESTER, NEW YORK.

INTERNAL-COMBUSTION ENGINE.

1,161,335.

Specification of Letters Patent. Patented Nov. 23, 1915.

Application filed March 25, 1915. Serial No. 17,023.

To all whom it may concern:

Be it known that I, NATHANIEL R. POTTER, a citizen of the United States, and resident of Rochester, in the county of Monroe 5 and State of New York, have invented certain new and useful Improvements in Internal-Combustion Engines, of which the following is a specification.

This invention relates particularly to the 10 valve-mechanism of an internal-combustion engine, and the object of the invention is to provide valve-mechanism capable of operation at high speed and adapted to provide the minimum impediment to the inflow of 15 combustible mixture and the escape of the exhaust gases from the engine-cylinder.

To the foregoing end I employ a valve so formed as to provide an intake or exhaust opening which may be completely annular 20 in form, and which preferably extends entirely around the cylinder.

The invention also comprises obturating devices particularly adapted for coöperation with a valve of the type in question, 25 and operating automatically to seal the cylinder-port during the occurrence of high pressure in the cylinder, while not interfering with the movement of the valve in opening and closing the port.

30 Other objects, and the features of construction by which the several objects of the invention are attained, will be set forth in connection with the following description of the illustrated embodiment of the invention.

35 In the accompanying drawings:—Figure 1 is a vertical, median, sectional view of an internal-combustion engine embodying the present invention; Fig. 2 is a horizontal section on the line 2—2, excluding the cylinder-head, in Fig. 1, looking downwardly; and Fig. 3 is a detail sectional view on the line 3—3 in Fig. 2, but on a larger scale.

The invention is illustrated as embodied 45 in a single-cylinder engine, but it is equally applicable to multi-cylinder engines, with slight modifications in construction which will readily suggest themselves to those skilled in the art. The illustrated engine 50 has the usual cylinder 5, piston 6, connecting-rod 7, and crank-shaft 8, and the cylinder is inclosed in the usual water-jacket 9 and is provided with a removable head 10.

The cylinder-head is spaced a short distance 55 above the upper end of the cylinder, so as to provide an annular space 11 consti-

tuting a passage or port through which gases may flow into and out of the upper end of the cylinder, and this port communicates with an annular chamber 12, formed by a casing 13 surrounding the top of the cylinder and partly closed by the cylinder-head 10, as shown in Fig. 3. The chamber 12 has cylindrical inner and outer surfaces, and it constitutes a guide-way for an annular valve 16 having inner and outer surfaces fitting closely against the cylindrical surfaces of the valve-chamber. The valve 16 is fixed to the upper ends of slide-rods 17, and each rod is fixed, at its lower end, to a slide 18 which moves in a slide-guide 19 on the frame of the engine. Each slide 18 is provided with a cam-roller 20, engaging a cam-path 21 formed in the side of a gear 27 which meshes with a pinion 22 fixed on the 75 crank-shaft. This arrangement is such that the valve 16 may be moved vertically in the valve-chamber 12 at suitable times in the operation of the engine.

At the side of the cylinder inlet- and outlet-passages 14 and 15, respectively, are formed, these passages communicating, respectively, with the upper and lower parts of the valve-chamber 12, as shown in Figs. 1 and 2. When the valve is in its intermediate position, as shown in Fig. 1, communication between the valve-chamber and the cylinder is entirely closed, but when the valve is in its lowermost position, as shown in Fig. 3, the upper part of the valve-chamber forms an annular passage around the cylinder which communicates with the inlet-passage 14; while, on the other hand, when the valve is in the upper part of the valve-chamber the lower part of the valve-chamber 90 forms an annular passage communicating with the exhaust-passage 15.

An important feature of the arrangement above described resides in the fact that the valve, when in either its uppermost or lowermost position, is moved entirely clear of one of the margins of the cylinder-port, so as to afford an annular opening extending entirely around the cylinder, through which gases may be introduced or discharged, and thus the engine is adapted for operation at very high speed with a minimum amount of "wire-drawing" or of back-pressure due to the flow of the gases through the port. In order, however, that the valve may be drawn 105 entirely clear of the margins of the cylinder-port, while at the same time leakage past

the valve shall be effectually prevented when the valve is in closed position, special packing or obturating means are necessary.

Since the tendency in an internal-combustion engine is for leakage to occur outwardly, owing to the fact that the pressure within the cylinder, at least during the compression and working strokes, is greater than the external pressure, it is necessary in the present case that the packing-means, in order to be subjected to and held in operative position by the pressure, be mounted not in the valve-ring but in the stationary parts with which it co-operates, so that a packing must be located at each margin of the cylinder-port. This introduces, however, the difficulty that the valve-member is moved entirely out of engagement with the packing-devices alternately, and consequently these packing-devices must be of such a character as to permit the valve to be disengaged from them, and then reengaged, without injury to the packing-means or obstruction to the movements of the valve-member. The resilient packing-rings commonly used in internal-combustion engines cannot be used in the present construction, because they spring outwardly when released to a diameter substantially greater than that of the surface with which they co-operate. Accordingly, I employ obturating devices which have a diameter, when disengaged by the valve, which is not substantially greater than the internal diameter of the valve, so that the valve may be moved readily into and out of engagement with them, but which respond automatically to pressure in the engine-cylinder so as to expand and press tightly against the surface of the valve. As a preferred, though not essential, construction for this purpose I employ two continuous packing-rings 24, which may be made of cast-iron or any other metal having sufficient elasticity. These rings have beveled inner surfaces, as shown in Fig. 3, which are engaged by the beveled peripheries of annular pressure-members or diaphragms 25. These pressure-members are located in recesses in the cylinder-wall and the cylinder-head, and are fixed to these parts at their inner margins, by screw-threads or otherwise. The pressure-members have enough elasticity so that when subjected to a substantial pressure against their exposed surfaces they spring outwardly, and thus have a wedging action on the packing-rings 24 by which these rings are slightly expanded. This action occurs when the valve 16 is stationary, and therefore, although the expanding action may cause the packing-rings to press very firmly at this time against the valve, no wear on the parts is so produced.

Although the expansion of the packing-rings under the influence of pressure is very

slight, it is sufficient for the purpose, owing to the fact that it is practicable to fit these rings very closely to the valve-member, and to maintain the close fit for a long period of operation. Since the valve-member is subject to no unbalanced lateral force, the wear due to the pressure of gas against it is negligible, and accordingly it is not necessary to provide for any considerable range of movement in the expanding packing.

At all times when the valve is in movement to open or to close the cylinder-port the pressure in the cylinder is comparatively small, so that at such times the packing-rings are not forced into engagement with the valve, and the parts have merely a free running fit. This is sufficiently close, however, to prevent any substantial leakage during the portions of the cycle of the engine when the pressure in the cylinder is low.

In Figs. 1 and 2 the inlet- and exhaust-passages are shown in duplicate, in order to avoid the necessity of the gases flowing for any considerable distance through the valve-chamber 12, but this duplication of passages is not essential to the invention.

A useful characteristic of the valve-mechanism resides in the fact that the valve-member 16, in descending for the purpose of opening the cylinder to the inlet-passage, acts as a piston by which combustible mixture is drawn into the valve-chamber, so that at the instant of opening the cylinder-port the gases are already in motion in the proper direction, and thus the influx of the combustible mixture is accelerated.

I claim:—

1. In an internal-combustion engine, the combination, with a cylinder provided, adjacent its inner end, with an annular chamber; of an annular valve-member movable, in said chamber, longitudinally of the cylinder and closing said chamber against communication with the combustion-space of the cylinder when the valve-member is in one position; means for moving the valve-member entirely out of engagement with one portion of said chamber, whereby a continuous annular opening is provided for communication between the combustion-space and said annular-chamber, and expansible packing-means mounted in the cylinder at the margin of said chamber and engageable with the valve-member, the diameter of said packing-means when not under pressure, being substantially the same as the inner diameter of the valve-member, but said means being expansible under the influence of pressure in the cylinder.

2. In an internal-combustion engine, the combination, with an annular sliding valve-member, of a continuous elastic packing-ring having a normal diameter no greater than the inner diameter of the valve-mem-

ber, and a resilient diaphragm subjected to the cylinder-pressure and having a beveled surface engaging an inner surface of the ring, whereby the ring may be expanded into close engagement with the valve-member when the diaphragm is subjected to pressure.

3. In an internal-combustion engine, the combination, with an annular sliding valve-member, of a stationary packing in the form of a continuous elastic ring, closely but

freely engaging the valve-member; and means coöperating mechanically with said ring and adapted, when subjected to cylinder-pressure, to expand the ring.

In testimony whereof, I affix my signature in presence of two witnesses.

NATHANIEL R. POTTER.
